UNITED STATES PATENT OFFICE

BEN K. FORD, OF EAST ORANGE, NEW JERSEY.

CLOSURE-RETAINER FOR CONTAINERS.

1,287,946.

Specification of Letters Patent.

Patented Dec. 17, 1918.

Application filed June 26, 1918. Serial No. 242,103.

To all whom it may concern:

Be it known that I, BEN K. FORD, a citizen of the United States, and residing at East Orange, in the county of Essex and State of New Jersey, have invented a new and Improved Closure-Retainer for Containers, of which the following is a specification.

This invention relates to means for retaining the heads, ends or other closures in position in kegs, barrels, boxes, pails and other containers, and its object is to provide a retainer which will firmly hold the closure in position, which may be quickly and permanently secured in position, and which may be produced at small cost.

This retainer is folded up from a narrow strip of sheet metal to form a flange at the inner edge of the retainer which flange extends at right angles to the main portion of the strip, and a rib parallel to the flange and spaced therefrom sufficiently to receive the closure, the body of the retainer being secured against the inner side of the container in any desired manner, preferably by bending the outer edge thereof around the edge of the container with the outer edge of the strip forced into the material constituting the container.

In the accompanying drawing, Figure 1 is a view, partly in section and partly in perspective of a closure secured in position by this improved retainer. Figs. 2, 3 and 4 illustrate the steps employed to secure the retainer to the container. Similar reference characters refer to like parts throughout the several views.

While the drawing shows this invention embodied in a container of cylindrical form, it is to be understood that it may be used in connection with any type of container in which the closure is approximately at right angles to the wall of the container. The retainer is preferably rolled up out of sheet steel but may be produced in any other manner and of any other material. The retainers may be made continuous by welding together the ends of the strips or the ends may abut or lap.

A flange or shelf 1 is formed on the inner edge of the retainer to support the closure 2. Outside of the closure and intermediate the side edges of the retainer, and parallel to the flange 1 a rib 3 is formed, preferably by folding the sheet metal back upon itself and the metal is then bent so that the band 4 may

lie flat against the inner side of the container 5 adjacent its edge. The outer flange 6 of the strip at first extends at right angles to the band 4 and rests on the edge 7 of the container when the closure and retainer are positioned.

When the closure is to be secured to the container, the retainer with the closure in position will be inserted in the container until the flange 6 rests upon the edge of the container. A rotating metal disk 8 is then brought down onto the rib 3, as indicated in Fig. 2 and a bending roller 9 is pressed against the rotating edge of the flange 6 of the retainer, bending over the edge 10 thereof as shown in Fig. 3. A second roller 12 is then pressed against this flange and the edge 10 is forced into the material of the container.

The edge 13 (Fig. 2) of the disk 8 is preferably at an oblique angle to its face 14 as indicated by the line 15. As the rollers 9 and 12 press against the curved part 6 of the retainer, the inner band 4 will be bent inward to nearly the angle of the edge of the disk 8, pressing the rib 3 against the closure to grip it firmly. The corner of the retainer between the rib 3 and band 4 will be pressed into the side of the container, as indicated in Figs. 1 and 4, and thus assist in securing the retainer in position.

It will be noticed that this retainer is made up of two parts, each substantially U-shaped in cross section, of which one is constituted by the flange 1 and rib 3 and the metal between them, while the other is made up of the band 4 and flange 6. These two parts are, of course, integral with each other. The proportions and sizes of the various parts of this retainer may be modified to meet various conditions without departing from the spirit of my invention set forth in the following claims.

I claim:

1. A closure retainer for containers comprising a strip of sheet metal fitting throughout its width against the inner side of the container around the opening to be closed and comprising two portions integral with each other and each substantially U-shaped in cross section, one of the portions being bent around and secured to the outer edge of the container with the outer edge of this portion forced into the outer side of the container, the inner portion having two parallel ribs or flanges, one on each side of the

closure to hold it securely in position, the flange on the outer side of the closure being formed of two thicknesses in engagement with each other.

5. 2. A closure retainer for containers comprising a narrow ring of metal fitting throughout its entire width against the inner side of the container and having one edge folded around and engaging into the

edge of the container and the other edge in the form of a radial flange to support the closure, the intermediate portion of the ring being folded so that the metal forming the two parts thereof is flat upon itself to constitute a radial rib parallel to said flange to extend on the opposite side of the closure from the flange.

BEN K. FORD.
